UNITED STATES PATENT OFFICE

2,440,914

EXPANSIBLE LAP

Arthur Ringzelli, Chicago, Ill.

Application February 8, 1945, Serial No. 576,748

7 Claims. Cl. 51—184.1

1

This invention relates to laps or finishing tools such as commonly used for lapping or polishing surfaces of holes in work pieces, or the like.

The objects of this invention are to provide an improved tool of the character indicated which will be particularly simple in construction and economical to manufacture, and which will be durable and efficient in use; to provide a lap having a cylindrical portion with outlets in the sides thereof and having an expansible and replaceable insert or plug with means for expanding the same; to provide a lap which may be easily and quickly adjusted without removing the same from the drill or machine tool; to provide a lap having means for supplying abrasive material from a central chamber; and to provide such other novel features and improvements in operation as will be described more fully hereinafter.

In the accompanying drawings illustrating this invention,

Fig. 1 is an expanded view showing the several parts of the lap;

Fig. 2 is a side view with parts broken away to show the interior construction;

Fig. 3 is a cross sectional view taken on the line 3—3 of Fig. 1;

Fig. 4 is a cross sectional view taken on the line 4—4 of Fig. 2;

Fig. 5 is a side view partly in section showing the lap in operating position in a drill press; and

Fig. 6 is a detail showing a modified form of compressing or expanding pin.

In the particular form of the invention as shown in these drawings, the lap comprises a rod 7 which is shouldered at its upper end as shown at 8 for engagement with the drill chuck 9. The lower end of the rod has a longitudinal bore or recess 10 which may conveniently be formed by drilling. The sides of the cylindrical portion have a plurality of longitudinal slots 11 which terminate at a short distance from the end of the lap. An expandable and replaceable plug 12 is inserted in the hole 10 and engages with the bottom of the hole 11' as shown in Fig. 2. This plug may be made of any suitable material, but preferably of rubber impregnated with an abrading or polishing substance such as emery or the like. A pin 13 which is knurled as shown at 14 fits tightly in the end of the lap and engages with the plug 12.

This pin serves to compress and expand the plug 12 which in turn expands or bulges out the segments or lands 17 of the lap between the slits 11. This provides a desirable barrel shaped work engaging surface as will readily be seen from Figs. 2 and 5.

2

When the lap is to be used, it is preferably placed in a drill chuck 9 and extends through a hole 15 in a work piece as indicated at 16 for the purpose of lapping the sides of such hole. The plug or cartridge 12 may be compressed to such a degree that portions thereof will be extruded through the slits 11 so that the abrading or polishing material will come in contact with the surface of the hole. Additional lapping material may also be supplied in the usual manner. After the lap has been used for a given length of time, it is frequently desired to expand or enlarge the same. In the present instance, this is readily accomplished by moving the drill chuck 9 downwardly until the end of the pin 13 engages with the bed plate 18 and may be forced further inwardly by pressure against the bed plate.

After the impregnated plug or insert 12 has been compressed or expanded several times for adjusting the size of the lap, it may be desirable to remove the same and insert a new plug. This may be readily done, and the new plug will provide a further supply of emery or abrasive material. The longitudinal or straight knurling of the adjusting pin permits it to be adjusted or replaced in the lap with sufficient friction to hold it in adjusted positions. This provides means whereby the lap may be quickly adjusted without being removed from the machine tool.

The pin 13 is shown with a flat or square engaging end which is desirable if the plug 12 is formed of rubber, but in some instances, I may use a pin 19 as shown in Fig. 6 with a sharp or pointed end 20 for engagement with the plug. This may be desirable if the plug is made of wood, or other similar material in which case the sharpened end will serve to more readily expand the end of the plug.

Having thus described my invention which, however, may be modified within the terms of the following claims, what I claim is:

1. A lap, comprising a rod having a recess at one end with longitudinal slits terminating short of the end, a plug formed of resilient material impregnated with an abrasive in said recess, and an expanding pin engaging with the end of the lap and abutting against said plug which serves to expand the plug and adjacent walls of the lap, and to extrude abrasive impregnated portions of the plug through the slits.

2. A tool, of the character set forth, comprising a rod shouldered at one end and having an integrally formed cylindrical portion at the opposite end, said cylindrical portion having longitudinal slits providing a plurality of lands or

working surfaces, an expansible insert formed of a resilient material impregnated with a lapping substance in said cylindrical portion, and a pin fitting closely in the end and engaging with said insert for expanding the same and causing portions thereof to project through the slits.

3. A lap, comprising a rod having a cylindrical portion at one end with openings through the walls thereof, a plug formed of rubber impregnated with emery in said cylindrical portion, and an expanding element engaging closely with the open end of the cylindrical portion and adapted to be pressed against the plug whereby the sides of the cylindrical portion may be expanded and portions of the plug may be forced out through said openings so that the emery may come in contact with the surface of the hole being acted upon.

4. In a lap, the combination of a tubular body having a plurality of substantially longitudinal slits which terminate at a distance from the ends thereof and provide circumferentially arranged work engaging lands forming a lapping portion and having an abutment formed integrally therein, an expansible insert formed of resilient material in said body and engaging said abutment, and expanding means engaging with the end of the tubular body and with said expansible insert for compressing the insert and expanding the sides of the body to adjust the effective diameter of the lapping portion of the lap.

5. In a lap, the combination of a rod portion having a shoulder at one end and having a longitudinal recess at the opposite end with slits extending through the walls of the recess, to provide a plurality of work engaging lands, a pin

extending into the recess and having a knurled portion engaging with the outer end thereof, and resilient expansible means between the inner end of the pin and the bottom of the recess adapted to be compressed and expanded by the pin for expanding the side walls of the recess to provide a barrel shaped work engaging surface.

6. The combination with a press, of a lap having a shouldered end engaging with the chuck of the press and having a downwardly extending integrally formed cylindrical portion provided with slits forming a plurality of expansible lands, an insert formed of resilient material in the cylindrical portion, an expanding pin fitting tightly in the cylindrical portion and extending therefrom which is adapted to engage with the insert and with the bed of the press, the arrangement being such that the lands may be expanded by forcing the expanding member against the bed whereby the lap may be adjusted without being removed from the press.

7. A device, as per claim 2, in which the pin has a sharpened engaging end, as described.

ARTHUR RINGZELLI.
